UNITED STATES PATENT OFFICE.

HARRY D. MORSE, OF LYNN, MASSACHUSETTS, ASSIGNOR TO HARWOOD COUNTER COMPANY, OF LYNN, MASSACHUSETTS, A CORPORATION OF MASSACHUSETTS.

COUNTER-SKIVING MACHINE.

Application filed March 17, 1926. Serial No. 95,226.

This invention relates to a machine for skiving a counter first along one longitudinal edge and then along the opposite edge, the counter being first moved in a straight path 5 through a portion of the machine while its straight edge portion is being skived, and then in a different and irregular path while its opposite edge portion, including its end portions, are being skived. A machine organized to skive the two edge portions during a continuous pass of the counter through the machine, is hereinafter referred to as the Stewart machine, and is disclosed by the Stewart Patent No. 653,892 dated July 17, 15 1900.

The invention relates to the straight edge skiving portion of the Stewart machine and is embodied in the improvements hereinafter described and claimed.

20 Of the accompanying drawings forming a part of this specification,—

Figure 1 is a top plan view of the flanged yoke, the deflecting roll, and two of the top-guiding rolls, hereinafter described, constituting members of the straight edge skiving portion.

Figure 2 is an edge view of the same.

Figure 3 shows in side elevation, the straight edge skiving portion including the members shown by Figures 1 and 2.

Figure 4 is a top plan view of the straight edge skiving portion omitting the rolls shown at the left in Figure 3.

Figure 5 is a plan view of a skived counter.

The same reference characters indicate the same parts in all of the figures.

12 designates the skiving knife which forms the straight skived edge portion 13 of a heel counter 16. The knife is fixed to the frame 14 adjacent to the nip of a pair of driven feed rolls 15, which engage the counter 16 and force it in a straight path against the knife. Journalled in fixed bearings on the frame are a front lower guide roll 17 and a rear lower guide roll 18, said rolls being arranged as shown by Figure 3 to support the skived portion of the counter, and positively driven with the feed rolls, the direction of rotation being indicated by arrows in Figure 3. Between the front and rear rolls is a similarly driven intermediate guide roll 19. 20 designates a swinging yoke pivoted on a stud 21 supported by standards 220 on the frame. The neck portion of the

yoke is provided with a flange which overhangs the space between the skiving knife 12 and the front guiding roll 17. 23 designates a loose front upper guiding roll, having trunnions 24 journalled in bearings in the yoke 20 and arranged to hold the counter in contact with the front lower roll 17, downward pressure being exerted on the yoke by a spring 25. 26 designates a rear upper guiding roll journalled in bearings in yoke 65 arms 27 mounted to swing on the stud 21. The rear upper roll is arranged to hold the counter in contact with the rear lower roll 18, downward pressure being exerted on one of the yoke arms by a spring 28. Between 70 the front and rear rolls 23 and 26 is an intermediate upper roll 29 journalled in bearings in the swinging ends of yoke arms 30, which are pivoted on the trunnions 24. The intermediate upper roll is arranged to hold the 75 counter in contact with the intermediate lower roll 19.

When the straight edge 13 of a long counter is being skived, it is desirable that the upper rolls 23 and 29 be held in a raised 80 position so that they will not press the counter against the lower rolls 17 and 19. To this end an adjustable support 31 is provided, which is vertically adjustable on a fixed member 32 of the frame, and is arranged as shown by Figure 3 to bear on the under side of the flange 22. The support 31 is secured to the member 32 by a screw 33 passing through a vertical slot 34 in the stop. The support may therefore be adjusted upward to maintain the upper roll 23 in a raised position and prevent it from pressing the counter against the roll 17. There is also provided, as in the Stewart machine, a pin 38 constituting a support 85 which may be inserted in coinciding orifices in the yoke 20 and one of the yoke arms 30, the arrangement being such that when the pin is inserted, it supports the roll 29 in a raised position and prevents it from pressing the counter against the lower roll 19. The counter therefore bears loosely on the rolls 17 and 19 and is not otherwise controlled until it reaches the rear rolls 18 and 26 which are constantly in position to nip the counter. 100

The counter bulges upward from the skiving knife 12 toward the flange 22, and, when the rolls 23 and 29 are raised, the counter, not being confined by said rolls against the rolls 17 and 19, is liable to be displaced edge. 105 110

wise before its forward end is controlled by the rear rolls 18 and 26. To prevent this liability, I provide a deflecting roll 35 having trunnions 36 journaled in bearings 37 on the under side of the flange 22. The roll 35 projects considerably below the flange and its rolling contact with the counter prevents the latter from deviating from a straight course. When a short counter is to be skived, the support 31 is lowered and the pin 38 is removed to permit the rolls 23 and 29 to press the counter against the rolls 17 and 19. When this is done, the deflecting roll 35 acts only to direct the forward end 10 of the counter to the nip of the rolls 17 and 23.

It will be understood that the portion of the machine, which forms the skived portion 13^a on the upper edge of the counter, may 20 be as shown and described in the Stewart patent.

The present invention is differentiated from the Stewart machine chiefly by the support 31 and the deflecting roll 35, the support or pin 38 being present in the Stewart machine.

I claim:

In a counter skiving machine of the character stated, means for skiving a counter 30 along its straight longitudinal edge, com-

prising a skiving knife, driven feed rolls adapted to force a counter against a knife, driven lower guiding rolls journaled in fixed bearings and including a forward, a rear, and an intermediate roll, a pivoted yoke having a flange overhanging the space between the skiving knife and the forward lower roll, a forward loose upper roll journaled in said yoke and pressed toward the forward lower roll, a rear loose upper guiding roll journaled in pivoted yoke arms and pressed toward the rear lower roll, an intermediate loose upper guiding roll journaled in pivoted yoke arms and pressed toward the intermediate lower roll, movable supports adapted 40 to support the forward and intermediate upper rolls in raised inoperative positions and to permit said rolls to assume their operative positions, and a deflecting roll journaled in bearing on said flange and arranged to bear on the upper side of the counter between the skiving knife and the forward lower guiding roll, said deflecting roll being adapted to prevent edgewise displacement of the counter when the forward 50 and intermediate upper rolls are raised.

In testimony whereof I have affixed my signature.

HARRY D. MORSE.
